UNITED STATES PATENT OFFICE

EMIL HULTGREN AND HAROLD MIKKELSON, OF WARWICK, NORTH DAKOTA

RATCHET PINCH BAR

Application filed September 4, 1929. Serial No. 390,343.

This invention relates to tools designed for use in removing ties from railway tracks without disturbing the rails thereof, such tools otherwise being known as ratchet pinch bars.

The primary object of the present invention which constitutes an improvement upon our pending application, Serial No. 295,993, filed July 28th, 1928, is to provide a ratchet 10 pinch bar having a minimum of moving elements so that application of the device to a track rail and its operation for the removal of a tie from under the same may be quickly performed.

Another object of the invention is to provide an improved ratchet pinch bar which may be easily, quickly and inexpensively constructed and which will be strong and durable.

The invention will be best understood from a consideration of the following detailed description taken in connection with the accompanying drawing forming a part of the present specification with the understanding, however, that the invention is not confined to any strict conformity with the showing of the drawing but may be changed or modified so long as such changes or modifications mark no material departure from the salient features of the invention, as expressed in the appended claims.

In the drawing:—

Figure 1 is a view in side elevation of the ratchet pinch bar embodying the present invention showing the same applied.

Figure 2 is a sectional view taken upon the line 2—2 of Figure 1.

Figure 3 is a transverse sectional view showing the position of the pinch bar in the tool.

Referring more particularly to the drawing wherein like numerals of reference indicate corresponding parts throughout the several views, the numeral 1 indicates a railway track rail, the same being shown mounted upon a tie 2.

The device embodying the present invention comprises an elongated body indicated generally by the numeral 3 which is made up of a head piece 4 having a shank 5 and a

hook bill 6. The shank portion 5 is secured by riveting, welding or any other means between the spaced ends of a pair of parallel beams 7 the under edges of which are provided with the notches 8 to form ratchet 55 teeth 9. The other ends of the beams 7 are connected and held in spaced relation by a block 10 to which they are suitably secured.

Designed for use in association with the body 3 is a pinch bar 11 which comprises an elongated handle 12 having an offset pointed tip 13 joined thereto by a curved head portion 14 which is of materially greater weight than the handle and which tapers off to form the point 13, in the manner shown. This 60 head 14 which is designed to be disposed between the beams 7 has a plurality of apertures 15 formed transversely therethrough, one of which receives a transverse fulcrum pin 16.

In operation the track engaging head 4 is hooked over a rail, in the manner shown, so that the beams 7 extend transversely of the track and above the tie which is to be removed. Coacting with the head 6 for maintaining a firm engagement of the device with the head of the rail 1 are depending lugs or spurs 6' formed upon the lower edges of the beams 7. These spurs are so placed with respect to the inner face of the head 6 as to provide sufficient room for the snug engagement of the head of the track rail between them and the head 6 of the device. By this means accidental disengagement of the device from the track rail is prevented 75 and the device is also supported substantially in horizontal position. The pointed end of the bar 11 is then extended through the body between the beams 7 and the pin 16 inserted in the proper aperture 15.

The pointed end of the bar is then engaged in the tie and the pin 16 positioned transversely of the beams in suitably positioned notches 8 and the free upper end of the lever is then drawn backwardly so that the pin 16 will fulcrum against a pair of teeth 9 to force the point of the bar forwardly and thus eject the tie from beneath the rails.

From the foregoing description it will be readily seen that by the use of this pinch bar

and ratchet the track ties may be easily and quickly removed from position or placed in position as desired and the application of the tool to the track may be easily and quickly made.

Having thus described our invention, what we claim is:—

1. A ratchet pinch bar comprising an elongated body formed of a pair of beams arranged in spaced parallel relation, ratchet teeth formed along the lower edge of each beam, a head connecting said beam at one end and designed for engagement over a railway track rail, the other end of the body, when in use, being unsupported, a pinch bar having a handle terminating at one end in a head, said head being formed to provide a tie penetrating point offset a substantial distance from the line of the handle and further being adapted to be positioned between said beams, and a fulcrum pin carried by and extending through the head of the fulcrum bar adapted to engage certain of said teeth to provide a fulcrum point for the bar.

2. A ratchet pinch bar comprising an elongated body formed of a pair of beams arranged in spaced parallel relation, ratchet teeth formed along the lower edge of each beam, a head connecting said beams at one end and designed for engagement over a railway track rail, said beams having depending portions on their lower edges coacting with said head to engage the track rail, the other end of the body, when in use, being unsupported, a pinch bar having a handle terminating at one end in a head, said head being formed to provide a tie penetrating point offset a substantial distance from the line of the handle and further being adapted to be positioned between said beams, and a fulcrum pin removably extended through the head of the pinch bar and adapted to be adjustably mounted in the bar in one of a series of transverse apertures formed therethrough for engagement with said teeth to provide a fulcrum point for the bar.

3. A ratchet pinch bar, comprising an elongated body formed of two flat beams disposed in spaced parallel relation, a spacing block between said beams at one end, a rail engaging head at the other ends of said beams, said head being substantially J-shaped and having the shank portion thereof disposed between the ends of the beams, the laterally extending portion of the head being adapted to engage across the ball of a rail, a lug formed on the lower edge of each of said beams for coaction with the rail engaging portion of the head to hold the rail thereagainst, a plurality of teeth formed in the lower edge of each beam, a pinch bar having a relatively long handle and a head at one end and extending obliquely thereof, said head terminating in a rail penetrating point and said head further being of a width to snugly position between

said beams, and a pin member extending transversely through said head and adapted to have its ends engage the teeth of the beams.

In testimony whereof we hereunto affix our signatures.

EMIL HULTGREN.
HAROLD MIKKELSON.
